DESIGN FOR AN ASH TRAY

David A. Jacobs, Cleveland, Ohio, assignor to The Safe-Out Ash Tray Company, Cleveland, Ohio,
a Corporation of Ohio

Application June 7, 1933. Serial No. 48,307

Term of patent 3½ years

To all whom it may concern:

Be it known that I, David A. Jacobs, a citizen of the United States, residing at Cleveland, in the county of Cuyahoga and State of Ohio, have invented a new, original, and ornamental Design for Ash Trays, of which the following is a specification, reference being had to the accompanying drawing, forming part hereof, wherein Fig. 1 is a plan view and Fig. 2 is a side elevation of such ash tray.

I claim:

The ornamental design for an ash tray substantially as shown.

DAVID A. JACOBS.
